UNITED STATES PATENT OFFICE.

GEORGE CASWELL, OF DAYTON, OHIO.

CIGAR-MACHINE.

SPECIFICATION forming part of Letters Patent No. 436,559, dated September 16, 1890.

Application filed April 25, 1890. Serial No. 349,535. (No model.)

To all whom it may concern:

Be it known that I, GEORGE CASWELL, of Dayton, in the county of Montgomery and State of Ohio, have invented certain Improvements in Cigar-Machines, of which the following is a specification.

This invention relates to what are generally known as "stationary" belt machines, in which a slack belt to form the wrapper is arranged above a bed or table fixed at its ends and combined with a traveling roller, by which it is caused to partly envelop and rotate the bunch while carrying the same over the bed.

The invention consists in various details of construction, among others the arrangement of the bed and various operating parts in an inclined position that the traveler may be operated by gravity, in a construction which admits of the machine being varied in width to produce cigars of different lengths, and in various details.

In the accompanying drawings, Figure 1 is a perspective view of my machine. Fig. 2 is a longitudinal vertical section of the same on the line 2 2, the parts being in position for the introduction of the tobacco. Figs. 3 and 4 are longitudinal vertical sections showing in outline the apron and the traversing roller at different stages of the operation. Fig. 5 is a transverse vertical section on the line 5 5, Figs. 1 and 2.

Referring to the drawings, A A' represent two vertical side plates or frames, each formed with a longitudinal inclined slot a, and with a longitudinal flange or shoulder a' on the inner side, as shown in Fig. 5.

B B' are two overlapping plates attached to the upper inclined edges of the respective side frames and forming jointly a bed or table, the width of which may be varied by changing the distance between the side frames. These frames are rigidly connected, and variation in the distance between them provided for by two arms c, extending horizontally inward from frame A and overlapping corresponding slotted arms c', which are projected from frame A' and connected by screws c² to the first-named arms. The slots and screws admit of the arms being extended or shortened at will to vary the width of the table, the sections of which, sustained at the outer edges by the arms, are free to slide upon

each other. At the lower end the table is formed with a transverse depression or pocket b to permit the introduction of the tobacco, 55 and at the upper end it has two depressed arms b', which receive and sustain the completed filler as it is released and delivered over the upper end of the table.

D represents the slack filler-forming apron 60 overlying the table, its upper end secured between clamping-bars E, seated in notches in the side frames, and its lower end clamped between bars n n', seated in notches in the under side of the side plates.

F is a transverse roller, traveling over and beneath which the apron is carried to form the usual pocket for the tobacco. This roller is mounted at its ends in vertically-adjustable boxes f, slotted and secured by screws f' to plates f², arranged to slide lengthwise on the side frames. These sliding frames are provided with journals f³, extending through the slots and carrying rollers f⁴, which travel on the flanges a' of the side frames, as shown 75 in Fig. 5. These rollers sustain and carry the principal part of the weight of the sliding plates and the top roller, and enable said parts to be carried easily to and fro and to descend by gravity to the lower end of the 80 bed after the completion of each filler. The rollers also bear beneath top flanges a² on the side frames to prevent the parts from binding under the upward pressure of the tobacco beneath the top roll. The journals of the 85 rollers are threaded and screwed into the ends of a connecting sleeve or nut G, by which they are adjusted endwise as changes in the width of the machine may demand. To this sleeve is attached a cord G', extended thence 90 upward over a guide-pulley H and downward to a foot-lever or treadle I, which is arranged so that when depressed it will cause the slides to advance and carry the top roll upward over the table. The pulley is mounted on a 95 rod g, seated at its ends in the side frames and provided with a series of holes to receive keys or pins g', which keep it in place, and by their changes in position from hole to hole admit of the side frames being moved.

In operating the machine the roller is permitted to gravitate to the position shown in Figs. 1 and 2, and the tobacco introduced into the pocket in the apron beneath the top

roll. The treadle is then depressed, causing the top roll to move upward over the table, in doing which the apron is caused to pay around the same and rotate the tobacco with 5 in the pocket, which is advanced in the apron until the upper end of the table is reached, when the filler is rolled out into the receiving-arms, the apron being released so that the filler may be removed.

Having thus described my invention, what I claim is—

1. In combination with the fixed side frames and table inclined, as described, the apron, the top roll, the gravitating roll supports or 15 slides, the cord to carry the slides upward, and a pedal to operate the cord.

2. The side frames, the table-sections attached thereto, and the cross-connections adjustable to change the width of the table, in 20 combination with the top roll, its sliding supporting-plates, the connection between said plates adjustable, as described, to suit the varying width of the table, and the belt.

3. The side frames having the inclined slots, and the longitudinal top and bottom shoulders projecting laterally from the frames, in combination with the rollers mounted to travel between the said shoulders, the table, the apron, the side plates carried by the rollers by means of connections extending through 25 the slots, and the top roll.

4. In a cigar-machine, a fixed inclined table with a pocket or depression at the lower end, in combination with an overlying apron fixed at its ends, inclined side guides, a top 35 roll, supports for said roll mounted to travel on the side guides and to descend by gravity, and means for carrying the roll and its supports upward.

In testimony whereof I hereunto set my hand, this 14th day of April, 1890, in the presence of two attesting witnesses.

GEORGE CASWELL.
